Oscar A. Bigler Inventor

By his Attorney
W. W. Mills Jr.

UNITED STATES PATENT OFFICE.

OSCAR A. BIGLER, OF WYOMING, OHIO.

BATHING CAP.

Application filed December 21, 1926. Serial No. 156,189.

This invention relates to bathing caps and is addressed to providing a bathing cap, that while adapted to fit heads of various sizes, is addressed more particularly to providing a 5 bathing cap that will fit tightly to the wearer's head so as to prevent access of water under the cap.

By this invention, a cap of any desired form or shape may be used; thereby, affording 10 means for either making the cap fancy or plain as desired.

In the accompanying drawing, as shown in Fig. 1, is the cap and in Fig. 2 a cross-section of same. In the drawing A is the cap proper, 15 which is made of any suitable flexible water-proof material. B is the brim or lower portion, which, as shown, encloses on all, except the inner side, a tube C. This tube C is of a flexible water-proof elastic material, such 20 as rubber, which is easily expanded or inflated by air or gas of any kind. D is an ordinary valve to permit the gas or air to be injected into tube C and when the requisite amount has been so injected, the valve is 25 closed. Likewise, the tube may be deflated by opening the valve and permitting the escape of the air or gas. The brim or outer portion B which encloses the tube C on all but the inner side which contacts with the wearer's 30 head is of an inelastic material so that inflation of the tube C results in reducing the diameter of that portion of the cap which contacts with the wearer's head and by reason of the tube being of an elastic or rubber like 35 nature, it readily conforms to the configuration of the wearer's head and is held thereby by the flexible, water-proof, inelastic portion B as will be readily seen, the portion of the tube C contacting with the wearer's head 40 may be increased or decreased and the pressure on the wearer's head likewise increased

or decreased by the addition of air or gas to increase the inflation of the tube or by permitting the air or gas to escape so as to decrease the inflation. This also provides for adjusting the fit of the cap to the wearer's head, while at the same time creating a water seal. The inflated tube C also serves to assist the bather in floating by its buoyancy.

In place of, or in addition to, the inelastic 50 outer portion B, I may provide, when desirable, an inelastic adjustable band or tape E. When this is provided, the band portion B may be either elastic or inelastic material as this adjustable tape E provided with a 55 buckle F serves to control the size of the cap.

I claim:

1. A bathing cap composed of a flexible water-proof head covering, a band therefor arranged entirely on the outside of said head 60 covering portion so as to provide a non-obstructed inner surface to said head covering portion, said band consisting of a water-proof elastic portion adapted to be inflated to conform to the wearer's head and a flexible 65 water-proof inelastic portion surrounding said inflatable portion on three sides thereof.

2. A bathing cap composed of a flexible water-proof head covering, and a band therefor arranged entirely on the outside of said 70 head covering portion so as to provide an uninterrupted surface on the inside of the said head covering portion, said band provided with means adapted to be inflated to force the head covering portion to conform to the 75 wearer's head and means preventing the inflation of said inflatable means in any direction other than toward the head of the wearer.

In testimony whereof, I have signed my name to this specification.

OSCAR A. BIGLER.
